(57) **CLAIM**

The ornamental design for a glove with mirror as shown and described.

DESCRIPTION

FIG. 1 is a rear perspective view of a glove showing a first embodiment of my new design;

FIG. 2 is a front perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top elevation view thereof; and

FIG. 8 is a bottom elevation view thereof;

FIG. 9 is a rear perspective view of a glove showing a second embodiment of my new design;

FIG. 10 is a front perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top elevation view thereof; and

FIG. 16 is a bottom elevation view thereof;

FIG. 17 is a rear perspective view of a glove showing a third embodiment of my new design;

FIG. 18 is a front perspective view thereof;

FIG. 19 is a front elevation view thereof;

FIG. 20 is a rear elevation view thereof;

FIG. 21 is a left side elevation view thereof;

FIG. 22 is a right side elevation view thereof;

FIG. 23 is a top elevation view thereof; and

FIG. 24 is a bottom elevation view thereof;

FIG. 25 is a rear perspective view of a glove showing a fourth embodiment of my new design;

FIG. 26 is a front perspective view thereof;

FIG. 27 is a front elevation view thereof;

FIG. 28 is a rear elevation view thereof;

FIG. 29 is a left side elevation view thereof;

FIG. 30 is a right side elevation view thereof;

FIG. 31 is a top elevation view thereof; and,

FIG. 32 is a bottom elevation view thereof.

The broken lines at the lower and upper extremities of the glove represent unclaimed boundaries of the design. The

(Continued)

broken lines showing cuff, interior and finger configurations are for environmental purposes only and form no part of the claimed design.
